UNITED STATES PATENT OFFICE

AUGUSTINUS EDWARD JONSSON, OF LIDINGO, SWEDEN

VACUUM DRYING APPARATUS

Application filed June 1, 1928, Serial No. 282,139, and in Sweden June 13, 1927.

The present invention relates to improvements in vacuum drying-apparatus of the type which includes a rotating or oscillating cylinder containing radially placed heaters. 5 The invention is essentially characterized by the fact that these heaters are removably mounted in the cylinder by sliding movement longitudinally thereof. In the embodiment here shown the heaters may be maintained 10 in the desired position by suitable guides.

These heaters, which are hollow and are supplied with a suitable heating-fluid, for instance hot water, steam or the like, may, if desired, be connected in series or in parallel. In order to increase the heating-surface, each of the heaters may for instance consist of two headers adapted for the heating-fluid and communicating by means of pipes. The heaters may, however, also be constructed in other ways, for instance in the shape 15 of flat chambers having about the same length as the drying-cylinder. In this case pipes, having open ends, may pass transversely through the chambers, the material to be evaporated, flowing through said pipes.

Other features of the invention will be more particularly set forth in the following in connection with the embodiments shown in the annexed drawings.

Fig. 1 shows the vacuum drying-apparatus as a whole, in side view, Fig. 2 being a cross-section of the same. Figs. 3 and 4 illustrate a heater in detail, looking from the side and from one end respectively.

Figs. 5 and 6, and 7 and 8, further show two modifications of the parts shown in Figs. 3 and 4 in similar views.

The drying cylinder 1 is mounted to rotate on rollers 2. This cylinder has no supporting shaft passing through it thus avoiding the difficulties attendant upon the use of such central shaft by reason of the necessity of employing a stuffing box at each end of the cylinder. This cylinder is given an oscillating motion by the motor 3 which is pref-

erably of the automatically reversing type. Heaters 4 of flat parallel sided form are supplied with steam, hot water, or any other suitable heating fluid by the flexible pipe 6 which is securely connected with the valved 50 distributing header 7' fixed on the head of the cylinder 1. Suitable pipes 7" connect this header with nipples 4' on the heaters 4. Similarly, suitable pipes 6' connect the nipples 4" with an exhaust header 6" mounted 55 on the head of the cylinder 1 and having a flexible exhaust pipe 6 leading therefrom. These heaters are interconnected by pipes 6" in such manner as to provide an efficient distribution of the heating fluid. Openings 8 60 are provided for the admission and discharge of the material to be dried.

The vacuum necessary to effect an efficient and rapid evaporation of the moisture in the material treated is obtained by the operation 65 of a suitable vacuum pump (not shown) connected to a condenser 9 which is in turn connected to the cylinder 1 by flexible exhaust pipes 10. This arrangement enables a high 70 vacuum to be obtained in the cylinder 1 so that the normal boiling point of the material being treated is greatly lowered. To guide the flexible pipes 6, 7 and 10 a bracket 11 of suitable type may be employed.

As has been previously stated, the heaters 75 are slidably mounted in the cylinder 1 so that they may be easily withdrawn or inserted whenever necessary, as in making repairs or replacements. Means are provided 80 to ensure that the heaters are properly positioned and securely held when inserted and to this end in the embodiment shown in the drawing this is effected by guides 14 and 15 arranged at the interior of the cylinder and at its centre respectively, the first-mentioned 85 guides 14 consisting of spaced flanges attached to the circumference of the cylinder. The guides 15 consist of ring-shaped discs which are attached to an axial central heating-chamber 16. As may be seen in the draw- 90

ings the heating-chambers 4 do not extend so far as to the side wall of the cylinder, so there is a space between the heaters and the said wall, this space being large enough to allow the material being evaporated or dried, for instance grain, to pass these spaces upon the oscillation of the cylinder, a fact of particular importance at the time of discharge of the material out of the cylinder. To realize a complete discharge of the drying-goods through the openings 8 inclined faces 17 may be placed near by the openings at the interior of the cylinder.

In order to increase the heating-power of the radially placed heaters said heaters may be constructed in such a way as to obtain a larger heating-surface than is obtained by the embodiments according to Figs. 1, 2, 3 and 4. So for instance the heaters may consist of headers 20, 21 and pipes 22 connecting the same with one another as shown in Figs. 5 and 6, or they may consist of flat parallel sided heaters having transversal conduits 23 provided with open ends and communicating with the cylinder space. These conduits 23 may be secured in position by punching holes in the walls of the chambers and bending the hole-edges inwards and welding the meeting edges 24 as clearly shown in Figs. 7 and 8.

To support the heaters safely the guides may also be arranged in such a manner as to extend along the whole or a part, respectively, of the sides of the heaters. Such an embodiment is particularly advantageous in the case of the heaters being carried out according to Figs. 5 and 6. The guides may, in this case, consist of plates which are, along the edges, turned towards the pipes 22, provided with semi-circular notches forming a sure support for the pipes.

Having now particularly described the nature of my invention and the manner of its operation, what I claim is:

45 1. In a device of the kind described, a cylindrical container, pairs of radially spaced guides arranged longitudinally of the container, and flat heating elements slidably mounted in said guides, the pairs of guides being spaced around the container.

50 2. In a device of the kind described, a cylindrical container, pairs of radially spaced guides arranged longitudinally of the container, and flat heating elements slidably mounted in said guides, the outer guides of said pairs consisting of members secured to the side wall of the container and provided with inwardly facing notches and the inner guides consisting of discs having peripheral notches facing the notches of the outer guides.

55 3. In a device of the kind described, a cylindrical container, pairs of radially spaced guides arranged longitudinally of the container, and flat heating elements slidably

mounted in said guides, the outer guides of said pairs consisting of members secured to the side wall of the container and provided with inwardly facing notches and the inner guides consisting of discs having peripheral notches facing the notches of the outer guides, said container having a central tubular conduit passing through the discs and supporting the same, said conduit having pipe connection to the several heaters.

AUGUSTINUS EDVARD JONSSON.
